[57] CLAIM

The ornamental design for a inflatable disk for advertising, as shown and described.

DESCRIPTION

FIG. 1 is a front elevational view of an inflatable disk for advertising showing my new design, and the cross-line shading on the front and rear sides which is partially shown for ease of illustration represented a conventional fabric and is understood to cover the entire area indicated;

FIG. 2 is a rear elevational view thereof;

FIG. 3 is a side elevational view thereof, with the opposite sides being a mirror image;

FIG. 4 is a perspective view thereof;

FIG. 5 is a perspective view thereof, with the article showing in closed condition;

FIG. 6 is a side elevational view thereof; and,

FIG. 7 is a perspective view thereof, with the sign shown in partially open condition.

FIG. 1

FIG. 2

FIG. 3

FIG. 4

FIG. 5
